U.S. Cl. D48—4

FIG. 1

FIG. 3

FIG. 2

FIG. 1 is a perspective view of a combined ballast support and bracket for a light fixture embodying my design, as seen from the back, one side and the bottom thereof;

FIG. 2 is a front elevational view thereof;

FIG. 3 is a rear elevational view thereof;

FIG. 4 is a side elevational view thereof;

FIG. 5 is a top plan view thereof; and

FIG. 6 is a bottom plan view thereof.

The pole in FIGS. 1, 2, 3, and 4, and the support arm in FIGS. 4, 5 and 6 are shown in broken lines for illustrative purposes only and form no part of the claimed design.

I claim:

The ornamental design for a combined ballast support and bracket for a light fixture, substantially as shown and described.
